GRAIN DRYING APPARATUS

Arthur B. Osgood, Minneapolis, Minn.

Application November 3, 1941, Serial No. 417,663

2 Claims. (Cl. 34—79)

My present invention relates to drying apparatus and provides certain improvements therein which especially adapt the apparatus for the treatment of corn, wheat, and similar grains. Generally stated, the invention consists of the novel devices, combinations of devices, and arrangement of parts hereinafter described and defined in the claims.

Corn, wheat, and similar grains very frequently and, in fact, usually contain more moisture than desired for storage or milling operations. In fact, some grains containing more than approximately 18% of moisture will not keep well in storage.

The drying is produced by a hot dry air blast. The grain is primarily subjected to the hot air blast by passing the same through a drier such, for example, as that known as the "Direct Heat Drier" through which the hot blast is caused to pass. The air blast acting on the grain as it passes through the drier will pick up and carry off dust, dirt, and the flakes or particles of the hull loosened from the grain and delivers the same to cyclone dust collectors. These cyclone dust collectors are placed in a closed chamber within which the air pressure is kept above atmospheric pressure, by the air blast; and hence, this chamber may be properly designated as a plenum chamber. This chamber is preferably provided with a hopper-like bottom and its walls are preferably well insulated so as to keep the dust collectors from low temperatures and the dust-laden air at relatively high temperature during the dust-collecting and separating actions.

A commercial embodiment of the invention is illustrated in the accompanying drawings where-in like characters indicate like parts throughout the several views.

Referring to the drawings:

Fig. 1 is a view, partly in side elevation and partly in vertical section, taken on the line 1—1 of Fig. 2, and with some parts broken away illustrating the improved apparatus;

Fig. 2 is a transverse vertical section taken on the line 2—2 of Fig. 1;

Fig. 3 is a horizontal section taken approximately on the line 3—3 of Fig. 1;

Fig. 4 is a fragmentary view chiefly in elevation but with some parts sectioned on the line 4—4 of Fig. 1; and

Fig. 5 is a fragmentary section taken on the line 5—5 of Fig. 4.

The various parts of the apparatus are preferably enclosed within a housing indicated as an entirety by the numeral 10. This housing, as

shown, is divided into two compartments 11 and 12 between which is a partition 13 having large air passages 14. Located in the compartment is a fan or blower (as shown of the "sirocco" type) and involving a motor-driven rotary head 15 and a casing 16. Casing 16 has an axial air inlet 17 and the outlet of said casing is in the form of a flaring shell 18 that affords a main air trunk 19 that delivers to the various ports 14 and through the latter to the chamber or compartment 12.

Extending vertically and horizontally of the air trunk 19 is a drier casing 20 that is preferably a rectangular sheet metal structure. Located within the drier casing or shell 20 is a multiplicity of inverted U-shaped baffles 21 which, as will hereinafter be noted, perform the dual function of deflectors for the corn or grain and for the air and also serve as open bottom air conductors or conduits.

In the front wall of the drier casing 20 are air ports 22 and in the rear wall thereof are similar air ports 23. The ports 22 open into the receiving ends of certain of the inverted U-shaped baffles 21 and the ports 23 open or lead from the delivery ends of others of said baffles. However, no one of the baffles has a port at both ends. As best indicated in Fig. 4, the receiving ports 22 open into the receiving ends of the one horizontal row of baffles and the discharge ports 23 lead from the delivery ends of other or adjacent horizontal rows. The importance of this relative arrangement will be made more apparent in the description of the operation.

The drier casing 20 is preferably formed with a hopperlike bottom adapted to be opened and closed by a gate or valve 24.

Located within the chamber or compartment 12 is a multiplicity of cyclone dust collectors 25 having tangential air intake ports 26 and tangential air discharge spouts 27, which latter preferably open outside of the compartment 12.

These cyclone dust collectors are of well-known or any suitable type and they are arranged in an upper series and in a lower series with corresponding upper and lower collectors in vertical axial alignment. The lower dust collectors are provided with hopper-like bottoms terminating in discharge necks 28, while the upper collectors have hopper-like bottoms with long tube-like discharge necks 29 that extend axially downward through the respective underlying dust collectors. All of the necks or tubes 28 and tubes 29 deliver to a common tubular conveyor spout 30, as best shown in Fig. 2. Working in the discharge tube 30 is a spiral conveyor 31.

The compartment 12 serves as a large settling chamber and is provided with a hopper-like bottom 32 that terminates in an open top discharge trough 33 in which works a spiral conveyor 34. The two spiral conveyors 31 and 34 will be power-driven through suitable transmission mechanism including, as shown, a sprocket chain 35 that runs over sprockets 36 and 37, respectively, on the projecting shafts of the conveyors 31 and 34. The discharge spouts or tubes 30 and 33 deliver to a common depending discharge spout 38.

To protect the mechanism within the compartment 12 from excessively low temperatures in cold weather, said chamber is shown as lined with insulating material indicated at 39. The corn or grain to be dried or treated may be delivered to the drier in any suitable way but, as shown, is arranged to be thus delivered through a supply pipe 40 extended from a suitable source of supply.

The air intake pipe 17 to the fan or blower, in practice, will lead from a source of hot dry air. In the operation of this apparatus, the hot air blast will carry the dust, lint, or foreign materials that have been loosened from the grain through and from the drier and into the plenum chamber 12, and from thence through the several cyclone dust collectors. The warm air thus delivered into chamber 12 will surround and keep the exteriors of the dust collectors warm so as to prevent condensation of the moisture until after it has passed through the dust collectors. Some of the dust or foreign materials will be precipitated onto the hopper-like bottom 32 and from thence into the discharge troughs 33. The materials discharged by gravity from the dust collectors will, of course, be delivered into the spout 30. The spout 30 and the trough 33 will, by the conveyors 31 and 34, be discharged into the common delivery spout 34 without opening the said trough and spout to the atmosphere.

Further comments

This pre-heated air is passed at high temperature and relatively low humidity through the grain column losing some of its original temperature and picking up moisture from the grain being dried. This operation also tends to dry the hull or outside shell of the grain, thereby making it brittle and much of this hull is picked up by the air and carried to the discharge side of the drier column. The spent air now contains a relatively lower temperature but a much higher relative humidity together with a considerable amount of light chaff and hull. The object of this is to remove this objectionable chaff or hull particles from the spent air and due to the relatively high humidity, it is necessary to separate the dust before any considerable loss in temperature causes a condensation and steam in the collector apparatus. In order to accomplish this, the plenum chamber, which houses the dust collectors, is insulated to prevent drop in temperature and the air is passed around the outside surface or surfaces of the collectors before entering the collector inlet to further prevent condensation in the interior of the dust col-

lectors. Since the plenum chamber is maintained at a pressure greater than atmospheric, it is also necessary to provide means for removing the dust from the cone outlets by some means 5 that will prevent a difference in pressure between the cone outlets and the atmosphere. This is accomplished by a screw conveyor connected to the dust outlets removing the separated dust and discharging it outside the plenum chamber.

10 The object of the hopper bottom in the plenum chamber with its open top screw conveyor is to remove the heavier dust particles which settle in the plenum chamber itself and passing the air through the chamber before entering the 15 dust collector. With this arrangement of equipment, condensation does not take place until the spent air is discharged from the outlets of collectors through the wall of plenum chamber to the outside. The collectors are, therefore, handling air of high relative humidity but without 20 water being condensed to interfere with the normal separation of dust in the collectors.

It is often desirable to cool the corn or grain after it has been dried and that may be readily 25 accomplished by providing a drier and air delivery device such, for example, as that already illustrated, and employing a drier casing 20' which may be a duplicate of the casing 29 and its ports and conduits. In Fig. 1 this lower casing 20' is shown as positioned as above indicated.

What I claim is:

1. In a drying apparatus, a plenum chamber, an upright drier having vertical passages for the gravity feed of grain or the like downward there- 35 through, and having transverse air passages, an air trunk spanning one side of said drier, said drier at its opposite side opening into said plenum chamber, means for producing an air blast in said air trunk and thence through said drier and the grain falling therethrough and from 40 thence into said plenum chamber, and a dust collector of the cyclone type, having an outer shell located within said plenum chamber, said shell having an inlet leading from the interior of said plenum chamber and having an outlet leading to the exterior of said plenum chamber.

2. In a drying apparatus, a plenum chamber, an upright drier having vertical passages for the gravity feed of grain or the like downward there- 45 through, and having transverse air passages, an air trunk spanning one side of said drier, said drier at its opposite side opening into said plenum chamber, means for producing an air blast in said air trunk and thence through said drier and the grain falling therethrough and from 50 thence into said plenum chamber, and a dust collector of the cyclone type, having an outer shell located within said plenum chamber, said shell having an inlet leading from the interior of said plenum chamber and having an outlet leading to the exterior of said plenum chamber, said plenum chamber having a hopper-like bottom with a discharge passage leading therefrom and the outer shell of said dust collector having a hopper-like bottom with a discharge passage 55 opening into the lower portion of said plenum chamber.

ARTHUR B. OSGOOD.
